ATTY'S.

UNITED STATES PATENT OFFICE.

KARL SCHLIEPMANN, OF ST. CHARLES, MISSOURI, ASSIGNOR TO ST. LOUIS CAR COMPANY, OF ST. LOUIS, MISSOURI, A CORPORATION.

CONVERTIBLE CAR SEAT AND BERTH.

SPECIFICATION forming part of Letters Patent No. 787,797, dated April 18, 1905.

Application filed January 3, 1905. Serial No. 239,525.

To all whom it may concern:

Be it known that I, KARL SCHLIEPMANN, a citizen of the United States, residing in St. Charles, in the county of St. Charles and State 5 of Missouri, have invented certain new and useful Improvements in Convertible Car Seats and Berths, of which the following is a full, clear, and exact description, reference being had to the accompanying drawings, forming 10 part of this specification.

My invention relates to a car-seat so constructed as to be converted into lower and upper sleeping-berths.

Figure I is a side elevation illustrating my 15 improvement with the parts shown in full lines in condition for service as a sofa and shown partly in dotted lines in condition for service as sleeping-berths. Fig. II is a vertical cross-section taken on line II II, Fig. I, 20 with the parts shown in condition for service as lower and upper berths. Fig. III is an enlarged vertical longitudinal section taken on line III III, Fig. II, showing in detail one of the hinge connections between one of the seat 25 end sections and upper-berth sections and one of the stays by which said sections are upheld in condition for berth service. Fig. IV is an enlarged vertical section taken on line IV IV, Fig. II, through one of the socket- 30 boxes in which the stays are fitted when the seat end sections are in position for berth service. Fig. V is a side view of the meeting ends of the seat and sections shown in 35 position for berth service and by which said sections are connected.

A designates the side wall of a railway-car containing at the location of the seats in the car windows B.

1 designates partitions that subdivide the 40 interior of the car into seat-compartments.

2 designates the bottom of a seat supported by a frame 3 and extending longitudinally of the compartment between pairs of the partitions 1.

45 4 designates end sections that surmount the ends of the seat-bottom 2. These end sections are swingingly connected to the partitions 1 by hinges 5, (see Fig. I,) and the lower ends of the sections are free of connection to the

seat-bottom, so that they may be swung from 50 an upright position at the ends of the seat-bottom, as seen in full lines, Fig. I, into horizontal positions at an elevation above the seat-bottom 2, as seen in dotted lines, Fig. I, and full lines, Figs. II and V.

55 6 designates stays that are pivoted at 7 to brackets 8, secured to the seat end sections 4 adjacent to their lower ends, as seen most clearly in Fig. III. These stays are free of connection with the seat end sections 4 at 60 their ends opposite those connected to the brackets and at these last-named ends are provided with hooks 9.

10 designates socket-boxes secured to the partitions 1 at the sides of the seat end sections 4, each box being provided with an opening, as seen most clearly in Fig. IV, through which the free ends of the stays 6 enter said boxes to permit of the hooks 9 engaging shoulders 11 at the bottoms of the 65 openings therein. In each socket-box is a door 12, that controls the opening into the socket-box, and to each socket-box is secured a spring 13, bearing against said door and serving to hold the door closed when the free 70 end of the corresponding stay is not seated in the socket-box.

75 14 designates a latch-bar, one end of which is pivoted to one of the seat end sections 4 at 15. (See Figs. I and V.) The latch-bar is 80 provided with a hook 16, pivoted thereto rearward from an extension-arm 14' of the latch-bar.

17 is a pin or button with which the latch-bar is adapted to engage, this pin or button 85 being set into the seat end section opposite to that equipped with the latch-bar.

18 is a stop secured to the seat end section equipped with the latch-bar and against which said latch-bar is adapted to rest when the seat 90 end sections are swung into horizontal positions and are connected by the latch.

When my convertible seat and berth is in use as a sofa, the parts thereof are in the condition seen in Fig. I, the seat end sections 4 being 95 in lowered condition, and the stays 6 are in folded condition at the rear of said end sections. When it is desired to convert the parts

into condition for service as lower and upper berths, the seat end sections are swung upwardly into horizontal positions, as seen in Figs. I, II, and V, thereby leaving the seat-bottom 2 unobstructed from end to end. The free ends of the stays 6 are then lowered and the hooks 9 introduced into the socket-boxes 10 to serve as supports for the seat end sections in their horizontal positions. When the seat end sections are raised into their horizontal positions, the latch-bar 14 is positioned with its free end lying upon the pin or button 17 in the seat end section containing it, and, due to the hook 16 of the latch-bar engaging said pin or button and the latch-bar resting against the stop 18, as seen in Fig. V, the meeting ends of the sections 4 are held firmly together in their horizontal positions.

I claim as my invention—

1. In a convertible car sofa and berth, the combination of partitions spaced apart, a seat-bottom located between said partitions, seat end sections hinged to said partitions above said seat-bottom and adapted to be swung upwardly into horizontal positions, stays hinged

to said end sections, and socket-boxes attached to said partitions and adapted to receive the free ends of said stays, substantially as set forth.

2. In a convertible car sofa and berth, the combination of a seat-bottom, seat end sections surmounting said seat-bottom and having hinged supports at their upper ends to permit of their being swung into horizontal positions, means for supporting said seat end sections in horizontal positions, and means for connecting the free ends of the sections when they are in horizontal positions; said last-named means comprising a latch-bar pivoted to one of the sections and provided with an extension-arm, a latch pivoted to said latch-bar rearward of the extension-arm, a pin on the other seat-section for engagement with said extension-arm and said latch, and a stop for engagement with the upper face of said latch-bar, substantially as set forth.

KARL SCHLIEPMANN.

In presence of—

H. F. VOGEL,
M. H. MURPHY.
